CLAIM

The ornamental design for a sandal-shaped faucet design, as shown and described.

DESCRIPTION

FIG. 1 is an isometric operational view of a sandal-shaped faucet design showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design.

The broken lines in FIG. 1 show environmental structure and form no part of the claimed design. The remaining broken lines represent parts of the sandal-shaped faucet design which form no part of the claimed design.
